GRINDING TOOL

Edward M. McGovern and Paul Schrick, Hillside,
N. J., assignors to Lempco Products, Inc., Cleve-
land, Ohio, a corporation of Ohio

Application December 17, 1938, Serial No. 246,373

3 Claims. (Cl. 51—184.2)

This invention relates to a grinding tool suitable for grinding shafts and other round objects to render them truly cylindrical. Our grinding tool, for instance, is well adapted for grinding the crankshafts of automobile engines.

In grinding crankshafts it is desirable to have a separable ring-like frame carrying on its inner periphery spring pressed shoes supporting abrading material. The separation of the frame allows the device to be passed around the crank shaft and then closed, making a complete ring about it, with the abrading material pressed against the shaft, whereupon rotation of the device grinds the shaft.

The object of our invention is to provide such a device in a simple and efficient form wherein the shoes and the abrading material carried thereby will be preserved in proper alignment and gradually pressed inwardly as the grinding proceeds.

Another feature of our invention relates to an efficient construction for readily rotating the grinding shoes while allowing them to move inwardly.

The invention will become more apparent from the following description, reference being had to the accompanying drawings illustrating a preferred embodiment of the invention.

In the drawings, Fig. 1 is a cross-section of our grinding tool in a plane at right angles to the axis 30 of the shaft to be ground; Fig. 2 is a diagrammatic cross-section of the tool as indicated by the line 2—2 on Fig. 1; Fig. 3 is a view illustrating the tool mounted on a crankshaft and driven by a belt from a motor; Fig. 4 is a fragmentary radial section through one of the grinding shoes and the driving frame, the plane of section being indicated by the line 4—4 on Fig. 4; Fig. 5 is a cross-sectional view of the tool on a plane normal to the plane of separation, as indicated by the line 5—5 on Fig. 1.

The frame of the grinding tool comprises a split pulley consisting of two half-ring members 10 and 11, each of which has formed in its outer periphery a groove 12 adapted to receive a driving belt. The two members are removably connected together by a pair of links 13 and 14, each of which is seated in a recess in the members and pinned thereto by two pins 15 and 16. The pins 15 are permanently attached so that the two links as shown comprise a rigid part of the member 11. The pins 16 are readily removable to allow separation of the two half-ring members. Each of these latter pins preferably has an enlarged head 17 normally occupying a counterbore in the member 10. When the pin is slightly shoved out from the opposite

side the head furnishes means for insertion of a screw driver or similar tool to withdraw the pin so that the parts may be separated.

The annular separable frame described carries two identical arcuate members 30, each of which is faced on its inner periphery by an arcuate shoe 31 secured thereto by screws 32. The member 30 and the shoe 31 constitute in practice a rigid member, but by making the shoes separable they may be replaced by shoes of different size to change the working diameter of the tool.

Each of the driven members 30 is formed with a pair of edge flanges 33 extending radially outward to provide a comparatively wide groove between them, in which the frame members 10 and 11 seat, as shown in Fig. 2.

One of the driven members 30 carries rigidly a pair of blades 40 which extend for the full width of the member 30 and project at right angles to the plane of separation of the two members. 20 These blades occupy grooves 41 in the other member 30 with an easy sliding fit. The blades operate to maintain these two members in accurate alignment and at the same time allow one to move toward and from the other.

The internal members 30 are driven by the annular frame and guided in their movement thereby by means of pins 18 on the annular frame members which occupy slots 35 in the members 30. The walls of these slots are normal to the plane of separation of the two halves of the device, and thus allow the members 30 and their shoes to move toward or from each other.

The shoes are pressed outwardly by compression springs 50. These springs occupy radial recesses in the members 10 and 11 respectively, and act on inwardly movable plungers 51 bearing against the members 30 at the base of the periphery grooves therein. The springs are compressed by plugs 52 screwed into the radial recesses.

Each shoe 31 carries suitable abrading material. This may readily comprise a strong piece of flexible emery cloth 60, one end of which is bent outwardly as at 61, across the end of the shoe, where it is clamped by a bar 62 secured by screws 63.

The two pieces of emery cloth are secured at diametrically opposite regions to the two shoes 31 respectively, as indicated in Fig. 1. When the device is rotated in a direction which will be counter-clock-wise in that figure, the emery cloth travels over the surface of the article being ground and the stresses maintain it smooth on the two shoes at the same time the springs 50

press these shoes inwardly to maintain the grinding action.

In Fig. 3 we have indicated at A a crankshaft to be ground. Our tool is opened by removing the two pins 16, then after being passed about the crankshaft it is locked by the return of these pins. Then the belt B may be passed about the frame 10 and 11 and passed over the driving pulley of the motor M, and the tool is ready to operate.

This tool is well adapted for grinding crankshafts of motor vehicles without removing the shaft and its bearings, it being merely necessary to remove the pan of the crankshaft housing and detach the connecting rods. Preferably the tool does not fill the entire space between the cranks and may be manually shifted back and forth as it rotates. During such operation, the flanges on the internal members and the interengaging 15 blades prevent wobble of the parts and preserve the grinding material in accurate cylindrical presentation to the shaft. At the same time, the power from the motor is readily transmitted from the rotary frame to the driven portion of the tool by the pins and slots described.

We claim:

1. In a grinding tool for shafts and the like, the combination of a split ring-like driving device, a driven device comprising separable arcuate members carrying abrading material, said arcuate members having flanges on each end confining the driving device therebetween, one of said devices having a pair of spaced slots on one side of the line of separation and the other

device carrying spaced pins projecting into said slots whereby the driving and driven devices are guided relative to each other, and spring means for moving the driven device into engagement with said shaft.

2. In a grinding tool a ring-like driving frame, an arcuate shoe carried by the inner periphery of said frame, said shoe having outwardly projecting flanges at each end thereof forming therebetween a groove for embracing the driving frame, each of said flanges having a pair of spaced parallel slots extending in a plane normal to the axis of said frame, spaced pins on said frame engaging in said slots, and means to move the shoe toward the work, said pin and slot connection guiding the shoe during said movement.

3. In a grinding tool, a ring-like driving frame, two arcuate abrasive carrying shoes carried by the inner periphery of said frame and forming a complete ring, each shoe having an outwardly projecting flange at each end thereof forming therebetween a groove embracing the driving frame, each of said flanges having a pair of spaced parallel slots extending in planes normal to the axis of said frame, spaced pins on said frame engaging in said slots, and means to move said shoes toward the work, one of said shoes having slots therein and the other having a blade secured thereto and freely occupying the notch in the other shoe whereby the shoes are guided upon movement relative to said frame.

EDWARD M. McGOVERN.
PAUL SCHRICK.
